WRENCH

William H. Boyles, Columbiana, Ohio

Application March 9, 1944, Serial No. 525,662

4 Claims. (Cl. 81—78)

1

The invention relates in general to wrenches, and more particularly to pipe wrenches for gripping and turning pipes and the like of various sizes.

The ordinary pipe wrench in common use includes serrated jaws for gripping the top and bottom of a pipe, the jaws being adjusted toward or away from each other by means of a thumb screw, and the jaws are adapted to be applied to the pipe from one side thereof for turning the pipe in one direction, but they must be applied to the pipe from the opposite side thereof for turning the pipe in the opposite direction.

Where a relatively large ordinary pipe wrench is applied to a soft metal pipe, such as brass, the jaw serrations are apt to be forced against the pipe too tightly, so as to crush or bend the same when the thumb screw is adjusted to grip the wrench jaws on the pipe.

It is an object of the present invention to provide a novel wrench which may be adjusted to fit varying sizes of soft metal pipes without danger of crushing or injuring the pipe.

Moreover, since the adjusting thumb screw of an ordinary pipe wrench is located near the jaws, in adjusting the wrench it is often inconvenient to reach the adjusting screw when the wrench is positioned on the pipe in a restricted space.

Another object of the present invention is to provide an improved wrench which may be adjusted from the end of the handle.

Another disadvantage of the ordinary pipe wrench is that in turning a pipe a partial turn at a time, when the wrench is shifted or retracted to grip the pipe for another partial turn, it is expedient, if not necessary, to hold the top jaw against the pipe to facilitate gripping the pipe at a new position.

This is often very difficult to accomplish when working in a restricted space.

Accordingly, a further object is to provide a novel wrench which may be retracted and gripped on the pipe for a series of partial turns, without holding the top jaw against the pipe.

In using an ordinary pipe wrench in restricted spaces, it often happens that there is space enough to apply the wrench to one side of the pipe for turning it in one direction, but that it is difficult, if not impossible, to apply the wrench to the opposite side of the pipe for turning it in the other direction.

It is, therefore, an important object of the present invention to provide a novel and improved wrench which is adapted to grip a pipe from one side, for turning the pipe either in one direction or in the opposite direction.

These and other objects are attained by the simple, inexpensive and easily operated structure which is shown, by way of example, in the ac-

2

companying drawing, and hereinafter described and claimed.

In general terms, the invention may be stated as including two bars mounted alongside each other, the one bar having a hooked jaw and the other bar having a wedge-shaped jaw end and movable relative to the hooked jaw for cooperating therewith to engage and grip a pipe positioned within the hooked jaw.

Referring to the drawing in which a preferred embodiment of the invention is illustrated:

Figure 1 is a front elevation of the improved wrench;

Fig. 2 is a side elevation thereof;

Fig. 3 is a fragmentary sectional view as on line 3—3, Fig. 2; and

Fig. 4 is a sectional view as on line 4—4, Fig. 2.

Similar numerals refer to similar parts throughout the several views of the drawing.

As shown in the drawing, the improved wrench includes a bar 5 having a handle portion 6 at one end and a hooked jaw portion 7 at the other end. A preferably straight bar 8 is positioned along the bar 5 at its hooked side, and the bar 8 has a handle portion 9 at one end and a wedge-shaped or inclined jaw portion 10 at its other end.

The handle portions 6 and 9 are preferably rounded and tapered, as shown, and may be provided with knobs 11 or the like to facilitate gripping the handle portions.

Preferably, the straight bar 8 is longitudinally slidably connected to the bar 5 by means of a U-shaped clamp 12, which is riveted or screwed, or otherwise attached, to the bar 5, as at 13 and which loosely engirdles the bar 8. Preferably the outer web 14 of the clamp 12 is provided with a rounded projection or indentation 15 for slidably abutting the outer surface of the bar 8, and the outer web 14 is spaced from the bar 5 a distance which will permit a certain amount of clearance between the bars 5 and 8 when the bar 8 is in abutment with the projection 15, as shown in Figs. 2 and 4.

Below the clamp 12, spring means is provided for urging the handle portions 6 and 9 apart and said spring means, preferably constitutes a curved spring plate 16, which is preferably attached to the bar 9 by means of screws 17, or the like.

The hooked jaw portion 7 of the bar 5 is adapted to take over a pipe or round bar, as indicated by the dot-dash lines 18 in Fig. 2, and the hooked jaw is provided with a serrated portion 19 for engaging the top side of the pipe and with a serrated end portion 20 for engaging the pipe below center.

Obviously, the hooked jaw 7 is adapted for fitting various sizes of pipe, for example, 1½" to 2" diameter for one wrench size, while another

wrench size may fit a range of pipe sizes below or above the range of $1\frac{1}{4}$ " to 2" diameter.

The wedge-shaped or inclined jaw 10 of the bar 8 is adapted to move up or down within the hooked jaw portion, and the inclined serrated surface 21 of the jaw portion 10 is adapted to engage the pipe surface on the side opposite to the serrated portions 19 and 20 of the hooked jaw 7. By moving the bar 8 up or down the jaw portion 10 is adjusted to grip various sizes of pipe, and the hooked jaw portion 7 is preferably provided with a recess 22 for receiving the end of the jaw portion 10 in gripping smaller sizes of pipe within the range of sizes for which the wrench is adapted.

A fulcrum projection is provided opposite to the serrated portion 20 at the end of the hooked jaw 7 and between the bars 5 and 8. The fulcrum projection may be formed on the bar 5 as indicated at 23 and provides a sharp edge engaging the inner side of the bar 8 at or adjacent to its jaw portion 10. Preferably the inner side of the bar 8 is provided with shallow serrations 24 for receiving the edge of the fulcrum 23 at various adjusted positions of the bar 8.

Preferably, an angularly disposed compression spring 25 is provided between the two bars 5 and 8 for urging the bar 8 outwardly and upwardly relative to bar 5. As shown, the spring 25 may be received in suitable recesses 26 in the bars 5 and 8, the ends of the spring being retained in counterbores at the ends of the recesses. The spring 25 is particularly desirable in larger wrench sizes, but may not be necessary in smaller sizes.

In the operation of the improved wrench, when the same is to be applied to a pipe such as 18, the bar 8 is moved downwardly to place its jaw end 10 in a position such as indicated at 10', and held in such position to enable the hooked jaw 7 to be positioned over and around the pipe.

The bar 8 is then released and moved manually or by the action of spring 25 upwardly until the inclined surface 21 of the jaw portion 10 is in position to engage the pipe 18.

With the jaws in this position, as shown in Fig. 2 in full lines, by gripping the handle portions 6 and 9 and squeezing them together, the jaw portion 10 of bar 8 will pivot about fulcrum 23 and the serrations on surface 21 will engage the pipe 18 so as to grip it securely between the jaw 10 and the jaw portions 19 and 20.

The serrations of the jaw portions 19, 20 and 21 are all formed so as to be directed substantially radially inward of the pipe, and accordingly when the pipe is gripped by squeezing the handle portions 6 and 9 the engagement of the pipe at the three spaced locations enables the pipe to be turned either in one direction or the opposite direction, that is, clockwise or counter-clockwise as viewed in Fig. 2.

When removing the wrench from a pipe, the bar 8 is pulled downwardly to the position 10', whereupon the hooked jaw may be lifted off the pipe.

As indicated in the drawing, the bar 5 is preferably thickened from a point beginning at the fulcrum 23 to a point on the other side of the recess 22, in order to strengthen the hooked jaw 7 for resisting bending moments set up when the wrench is applied to a pipe to turn the same.

Due to the fact that the bar 8 is pushed or moved by spring 25 upwardly into position to

grip a pipe, in adjusting the novel wrench, there is no danger of crushing a soft metal pipe as in the case of the ordinary pipe wrench, where the jaws are screwed toward each other.

5 The novel wrench is adapted to be adjusted from the end of the handle and may be applied to a pipe from one side for turning in either direction, so that it facilitates working in restricted spaces.

10 The improved wrench is simple and inexpensive to manufacture, and is easily operated.

I claim:

15 1. Wrench construction including a bar having a downwardly hooked jaw with spaced inner gripping portions at one end and a handle portion at its other end, a second bar extending along one edge of said first bar and having an inclined jaw at one end facing said hooked jaw and a handle portion at its other end, means slidably connecting said bars intermediate their ends for relative longitudinal movement, a projection on one of said bars for engaging the other of said bars adjacent its jaw end whereby movement of the handle portions of said bars towards each other causes movement of said inclined jaw toward said inner gripping portions of the hooked jaw, and means yieldingly urging the handle portions of said bars apart.

20 2. Wrench construction including a bar having a downwardly hooked jaw at one end, spaced gripping portions on the inner side of said jaw, a second bar longitudinally slidably connected to said first bar and extending along the edge thereof facing said hooked jaw, said second bar having an inclined jaw at one end for cooperating with said hooked jaw to grip opposite sides of a pipe at three spaced locations, a fulcrum projection on one of said bars for engaging the other of said bars adjacent its jaw end, and means yieldingly urging the other ends of said bars apart.

25 3. Wrench construction including a bar having a hooked jaw at one end for fitting around a pipe and the like, the outer end of said hooked jaw having spaced gripping portions adapted to engage one side of the pipe below and above its center, a straight bar longitudinally slidably connected to and extending along one edge of said first bar and having a wedge-shaped jaw portion on one end for entering the hooked jaw and engaging the pipe on the opposite side from the outer end of said hooked jaw, a fulcrum located between said bars adjacent their jaw ends, and said jaw portions having serrations directed substantially radially inward of the pipe for gripping the pipe to turn it in opposite directions.

30 4. Wrench construction including a bar having a hooked jaw portion at one end provided with spaced serrated portions for gripping one side of a pipe below and above its center, a second bar longitudinally slidably connected to and extending along one edge of said first bar and having an inclined jaw portion at one end for gripping the opposite side of the pipe and cooperating with said hooked jaw portion to grip the pipe at three spaced locations, spring means located between said bars urging said inclined jaw portion toward said hooked jaw portion, a fulcrum projection on one of said bars for engaging the other of said bars adjacent its jaw portion, and means yieldingly urging the other ends of said bars apart.

WILLIAM H. BOYLES.
